UNITED STATES PATENT OFFICE

92,559

DESIGN FOR A TRAILER

Harold H. Robinson, Coral Gables, Fla., assignor to Curtiss Aerocar Company, Inc., Coral Gables,
Fla., a corporation of Florida

Application February 28, 1934, Serial No. 50,899

Term of patent 14 years

To all whom it may concern:

Be it known that I, HAROLD H. ROBINSON, a citizen of the United States, residing at Coral Gables, in the county of Dade and State of Florida, have invented a new, original, and ornamental Design for Trailer, of which the following is a specification, reference being had to the accompanying drawing, forming a part thereof.

Referring to the drawing:
Fig. 1 is a top plan view;
Fig. 2 is a side elevation;
Fig. 3 is a front elevation; and
Fig. 4 is a perspective view.

I claim:

The ornamental design for a trailer as shown.
HAROLD H. ROBINSON.
